Francisco, Calif., a corporation of Delaware

Application May 27, 1939, Serial No. 276,062

4 Claims. (Cl. 260—683.4)

This invention relates to the production of improved fuels for gasoline engines and deals particularly with an economical method for producing fuel of high anti-knock value and lead susceptibility from unsaturated hydrocarbons boiling in the gasoline range such as cracked gasoline and the like and with novel hydrocarbon mixtures having such valuable properties.

There is a recognized need for gasoline powdered air and marine craft less subject to fire and explosion hazards, and in aircraft a need to overcome vapor lock difficulties such as are encountered as a result of the vacuum created in fuel feed lines and the like during sudden maneuvers at high speed. The perfection of fuel injection devices which can be used successfully to replace carburetion in gasoline engines has created a demand for a fuel of reduced flash point and vapor pressure to meet such need. It is feasible to so fractionate ordinary gasoline as to raise its flash point and make it suitable as a safety fuel as far as volatility is concerned. Such low vapor pressure gasoline has, however, knocking characteristics which render it unsuitable for fuel use. The present invention overcomes this disadvantage and provides safety fuels of high octane value which are remarkably responsive to addition of lead tetraethyl and the like and particularly useful as aviation gasoline free from vapor lock difficulties. It also provides an improved method for producing gasoline of conventional boiling range suitable for use in engines equipped with carburetors.

An important object of the invention is to increase the lead susceptibility and yield of gasoline obtainable from cracked gasoline or suitable fractions thereof and the like. Another object is to produce from such unsaturated products a stable, saturated fuel of high octane rating, and to produce such high quality fuel without undesirable formation of low or high boiling by-products. Still another object is the production of novel hydrocarbon mixtures which do not lose anti-knock value as a result of evaporation, as in storage and the like. Another object is to provide gasoline having a more uniform octane rating throughout its boiling range, particularly useful in reducing differences in operation of different cylinders resulting from non-uniform gasoline distribution. Other objects will be apparent from the following description.

In accordance with the present invention these desirable results may be advantageously achieved by reacting a mixture of hydrocarbons boiling

within the gasoline range and preferably containing a substantial quantity of normally liquid straight-chain olefines with an isoparaffin in the presence of a suitable alkylation catalyst such as concentrated sulfuric acid. In this way saturated addition products of such isoparaffin with the olefinic content of the gasoline or suitable fraction thereof being treated, may be formed having higher boiling points than the olefines from which they are derived. This is contrary to past experience in alkylation with olefines boiling within the gasoline range which has been confined to highly branched olefines such as di-isobutylene and the like which yield on reaction with isobutane, in the presence of sulfuric acid, preponderantly products having a boiling range the same as, or lower than, the starting olefine as a result of dealkylation, splitting or rearrangement reactions which take place under alkylation conditions. We have found, not only that the less branched olefines such as are present in cracked gasoline may be alkylated with isoparaffins such as isobutane and isopentane and the like to form valuable higher boiling products but also that by thus increasing the molecular weight of the hydrocarbons, their anti-knock value is not reduced as is usually the case when chain length is extended, but on the contrary, both the octane rating and lead susceptibility of the product may be increased compared with the cracked gasoline fraction from which they are derived.

In order to make the invention more clear it will be described in more detail with particular reference to its application to the reaction of cracked gasoline stock, including fractions thereof, with isobutane in the presence of concentrated sulfuric acid. It will be understood that this implies no limitation on the invention which is also applicable to other hydrocarbon mixtures boiling within the gasoline range and containing a substantial quantity of normally liquid straight-chain olefines regardless of their source. Dehydrogenation, for example, may be used in preparing starting material suitable for the present invention. Also other isoparaffins such, for example, as isopentane, 3-methyl pentane and the like may be used with the same or other suitable catalysts.

In reacting isoparaffins with cracked gasoline and the like in the presence of sulfuric acid of alkylation strength the olefines tend to form sulfonates or alkyl sulfates or polymers or other undesirable products which not only reduce the yield of desired alkylated gasoline but also re-

duce the catalytic activity of the acid. By providing a suitable molecular excess of isoparaffin to olefines these undesirable side reactions may be sufficiently suppressed so that the reaction may be made to go predominantly to alkylation and the catalyst protected. Generally molal ratios of isobutane to cracked gasoline olefines of at least 2:1 are preferred and more preferably ratios of the order of 20 or more to 1. Ratios in the range of 60:1 to 500:1 are particularly useful. It is preferable to pre-mix the cracked gasoline or equivalent starting material with a molal excess of the isoparaffin to be reacted therewith before contacting it with the catalyst acid. A suitable proportion of isobutane is at least two or preferably at least five mols of isobutane per mol of unsaturated hydrocarbon present in the gasoline fraction. More preferably ratios of ten to twenty or more mols of isobutane per mol of olefine are used.

The process is preferably carried out at a temperature below about 50° C. and more preferably in the range of about -20° to about +35° C. It is desirable to operate with the reactants in the liquid phase. Where sulfuric acid is used as the catalyst it is preferable to employ initial concentrations of the order of 85 to about 100% or more preferably 90 to 100% although fuming acid may be used at low temperatures. There appears to be an optimum combination of acid strength and temperature which may differ depending upon the particular olefines and isoparaffin used in the reaction. It is desirable to employ a volume excess of acid over reactants, and more preferably a volume excess of acid over hydrocarbons present in the reaction. About 0.3 to 4 or more volumes of concentrated sulfuric acid per volume of hydrocarbon present may be used although ratios of about 0.7:1 to 3:1 are preferred. It is usually preferable to carry out the reaction rapidly and to avoid further reaction of primary alkylation products with more olefine. Reaction times of a fraction of a minute to about 30 minutes may be used although times of the order of about 10 to 25 minutes are preferred.

Any suitable method of intimately mixing the reactants in the presence of the catalyst acid may be used. Mechanically stirred agitators may be used or the reactants may be flowed through suitable tanks or towers or the like containing packing or baffles capable of providing the desired intimate mixing. For large scale operations positive circulation by means of a pump or the like may be used to provide the required mixing and the reactor may take the form of a pipe coil or one or more tanks. For example, the reaction mixture may be pumped, preferably under conditions of turbulent flow, to a separator in which sufficient stratification is allowed to take place to permit separation of a hydrocarbon phase from which product may be removed equivalent to the feed and the remainder returned for mixing with fresh feed after which the mixture is recontacted with the acid phase and the cycle repeated. In such a system it is unnecessary to completely separate hydrocarbon from the acid in the stratifier. This method of operation has the advantage of providing pre-mixing of the cracked gasoline with a large amount of isoparaffin before it is contacted with the acid while also reducing the amount of hydrocarbon which must be removed to separate product from excess isoparaffin compared to once through methods of reaction.

While the process of the invention may be

carried out batchwise or intermittently, it is particularly adapted to continuous methods of operation. An especially advantageous method of continuous operation comprises circulation of a stream of reacted mixture through a suitable reaction system and continuously feeding into the circulating mixture the cracked gasoline to be treated and the isobutane to be reacted therewith, the latter preferably in large molecular excess over the olefinic content of the gasoline, while taking off, preferably at a point in the circuit sufficiently removed from the feed inlet to insure substantial reaction, reacted mixture from which hydrocarbon equivalent to the feed is withdrawn and the remainder returned to the system. By this method of operation a large recycle of thoroughly dispersed reacted mixture is provided to mix with the cracked gasoline being treated and the acid is maintained thoroughly mixed with isobutane throughout its time of contact with the gasoline so that alkylation of the olefines present in the gasoline is promoted and undesirable reactions such as olefine polymerization and/or sulfonation or sulfation are substantially suppressed. It also makes it unnecessary to separate unreacted isoparaffin from the reacted mixture in order to supply the desired large excess thereof in the reaction. Preferably a volume excess of circulating mixture of reaction products, acid and unreacted material over the volume of hydrocarbon feed and most preferably a volume excess of circulating hydrocarbon is used. Such operation provides a mass of circulating liquid so large that the heat of the reaction has but a small effect upon its temperature so that temperature control is easy. The circulating mixture of dispersed hydrocarbon and acid facilitates rapid uniform mixing of the feed with the catalyst in the presence of excess isoparaffin thereby reducing undesirable side reactions. It also reduces the power required for intimately mixing reactants and catalyst. This preferred method of operation has also the advantage of providing more uniform reaction time since inlet and outlet points may be so separated that short-circuiting may be avoided and incomplete or excessive reaction thus reduced.

The attached drawing illustrates, diagrammatically, an assemblage of apparatus which has been found to be particularly advantageous for the manufacture of gasoline in accordance with the process of our invention.

Cracked gasoline or a suitable fraction thereof from a source not shown is supplied by pipe line 1 to a mixing tank 2 where it is admixed with isobutane and/or isopentane-containing hydrocarbon introduced by pipe line 3. Excess isobutane and/or isopentane recovered from the alkylation treatment may advantageously be returned to the system at this point as by line 4. Reacted hydrocarbon phase containing unreacted isoparaffin and alkylation products may also be mixed with the feed as by lines 5 and 4. The resulting hydrocarbon mixture containing approximately at least 5, and preferably 10 or more, molecules of isobutane and/or isopentane per molecule of olefine is introduced by pipe line 6 into a circulating stream of a dispersed mixture of sulfuric acid of alkyllating strength and reacted hydrocarbon substantially free of olefines flowing in conduit 7 to the suction end of circulating pump 8. Pump 8 forces the resulting mixture through pipe line 9 and mixing device 10 which may be suitable mixing nozzles or the like, to pipe line 11 feeding into tank 12 which is pro-

vided with cooling means not shown. Such cooling means may be coils or tube bundles or the like through which any suitable refrigerant may be circulated. Thus, cooling water, brine or liquid butane, for example, may be used as the cooling agent to maintain a reaction temperature of about -10° to 50° C., preferably about 5° to 25° C. Instead of indirect cooling by means of such refrigerants, the cooling may be effected by evaporation of a part of the reaction mixture, for example, isobutane where such isoparaffin is used, or liquefied normally gaseous material may be injected into the mixture and evaporated to maintain the desired reaction temperature. A separate cooling unit in place of, or in addition to, cooling means in tank 12 may be provided either in line 7 or line 11 to cool the entire circulating mixture or preferably in a branch of the circuit through which a part of the circulating mixture may be by-passed and cooled sufficiently so that on remixing with the circulating mixture it produces the desired temperature therein.

The mixture from tank 12, still in a thoroughly dispersed state, passes through conduit 13 which is in communication with conduit 7. Pipe line 14 is provided for withdrawing a part of the dispersion from conduit 13 to separator 15 where stratification of the withdrawn reacted mixture takes place and separated acid phase is returned to conduit 7 by pipe lines 16 and 17. Valve controlled outlet line 18 and inlet line 19 are provided for withdrawing a part of the catalyst acid, if necessary, and its replacement by fresh or re-vivified acid of suitable strength. The hydrocarbon phase formed in separator 15 is withdrawn by line 20 to a scrubber 21 which is fed with caustic by line 22 to remove any entrained or still emulsified acid. In order to reduce the amount of unreacted isoparaffin separated from reaction product while still providing the desired high ratio of isoparaffin to olefines in the mixture prior to contact with the acid, a part of the hydrocarbon phase in line 20 may advantageously be conducted by lines 5 and 4 to mix with the feed. It is usually unnecessary to have complete separation of hydrocarbon from the acid in separator 15 and the acid phase returned to the reaction by lines 16 and 17 may be in an emulsified form with hydrocarbon.

The scrubbed hydrocarbon passes by line 23 to a fractionating column 24 in which materials boiling below the initial boiling point desired for the product are removed as overhead through line 25. Such overhead products will contain excess unreacted isobutane and/or isopentane which may advantageously be recycled to the alkylation

system. Where sources providing substantially pure isobutane and/or isopentane have been used it is feasible to return such excess directly by lines 25 and 26 to line 4 for admixture with the cracked gasoline to be treated in mixer 2. However, if the original isobutane and/or isopentane contains inert materials such, for example, as the corresponding normal paraffins or the like, it is usually desirable to conduct the overhead from column 24 by lines 25 and 27 to column 28 for removal of such diluents which may be taken off by line 29, while the thus purified isobutane and/or isopentane is fed by line 30 to return line 4. Where diluents having a lower boiling point than isobutane are present, another column, not shown, may be used for their removal before the isobutane and/or isopentane is returned to the system. We prefer, however, to use sources of isobutane and/or isopentane free from lower boiling hydrocarbons and for this reason preferably depropanize the isobutane used in order to prevent accumulation of propane in the system. The debutanized gasoline withdrawn as bottom product from column 24 by line 31 may have any desired initial boiling point since column 24 may be used not only for recovery of isobutane but also for separation of undesired lower fractions of the alkylated gasoline, such separated gasoline components being withdrawn from the system as bottom products from still 28 by line 29. The alkylated gasoline thus recovered by line 31 requires only removal of heavy ends in column 32 in order to obtain a finished product. Such product is recovered through line 33 while heavy ends are removed by line 34.

The following examples of typical applications of the process of the invention to the treatment of gasoline fractions produced by different cracking processes illustrate suitable methods for practicing the invention and show its advantages.

Example I

Various cracked gasoline fractions were treated in a reactor provided with internal cooling coils and a high speed stirrer and connected with a separator. In each case the reaction system was first charged with sulphuric acid of 98% concentration in the amount required to give the desired acid to hydrocarbon ratio when operating completely full. The liquid feed of cracked gasoline and isoparaffin was supplied continuously while acid layer from the separator was returned to the reaction system, and hydrocarbon phase was removed and fractionated. The reaction temperature was 10° C. and the contact time 20 minutes in all cases.

Example II

A West Texas reformed aviation gasoline boiling between 40° and 128° C. which had been phosphoric acid treated and sweetened and contained about 28% olefines was treated in a manner similar to that described in Example I except that 25 96.5% sulphuric acid was used at 20° C. The feed consisted of 57.7 weight per cent of aviation gasoline, 34% of a mixture of isobutane and isopentane and 6% of normal butane and pentane corresponding to a mol ratio of combined isobutane and isopentane to olefines of 4.2 to 1. The 30 mol ratio of isobutane and isopentane to olefines in the system was greater than 65 to 1. Using a volume ratio of acid to hydrocarbon of 0.7 to 1 a yield of 112% by weight of alkylation products based on the aviation gasoline was obtained with an acid consumption of one volume per 8.48 volumes of product. The product boiling above 130° C. had an A. S. T. M.=CFR octane rating of 89.8 compared with 72.0 for the depentanized original aviation gasoline.

It will be seen from a comparison of columns 3 and 4 of Example I that high ratios of isoparaffin to olefine in the feed are advantageous in increasing the yield and catalyst life and from columns 4 and 5 that a volume excess of acid over hydrocarbons in the reactor is desirable for increased yield. A comparison of column 1 with column 4 shows the materially increased acid life obtainable by the use of cracked gasoline fractions of the type used in these runs having an end point of 70° C. as contrasted with one of 100° C. and point. This was further established by tests made on the separated 70° to 100° C. fraction under identical conditions which gave a weight yield on gasoline used of 95% and only 3.2 volumes of product per volume of acid. The source of the cracked gasoline may influence the point of fractionation which will give the best results. It is usually advantageous to use cracked gasolines having an end point such that the alkylation products all boil within the gasoline range. Cracked gasolines of 150° C. end point or below may be used or more preferably those having end points of not more than about 100° C. Most preferable from the standpoint of long catalyst life are gasoline fractions boiling below 70 low 72° C.

By the process of the invention unstable, sour smelling, cracked gasoline of high sulphur content may be converted to a water white, sweet smelling saturated gasoline which is stable to 75

light and has a total sulphur content of 0.001% or less. As will be seen from the results of Example I, the process of the invention is capable of giving novel hydrocarbon mixtures the higher boiling fractions of which have an anti-knock value equal to, or greater than, that of the lower boiling fraction. Such mixtures do not lose octane rating on evaporation in storage and give more uniform operation in multi-cylinder engines where the gasoline distribution to the different cylinders is non-uniform. The products of the invention are particularly suitable for blending with iso-octanes and like high anti-knock value materials in the preparation of gasoline engine fuels of superior quality. They may also be blended with ordinary gasoline and may be used with di-isopropyl ether and like fuel components.

The higher boiling products produced in accordance with the process of the invention are particularly useful as safety fuel of low vapor pressure and high quality or as components of such fuel. Thus, for example, products obtained in Example I boiling between 100° and 200° C. may be used in safety fuel having a flash point (open cup) of 110° F. or higher and an octane rating of 80 to 90 without doping or 95 to over 100 by suitable addition of lead tetraethyl.

The invention is capable of variation not only in regard to the unsaturated gasoline which may be used and the conditions under which the reaction with isoparaffin may be conducted but also with respect to the method of operation employed. Thus, while the process may be conducted so as to give a completely refined, stable saturated gasoline in one operation, the use of suitable auxiliary treatments, such for example, as preliminary removal of valuable and/or undesirable constituents prior to or after alkylation may be desirable. Also other agents such, for example, as isomerization catalysts may be used either before, during or after the process of the invention. It will therefore be understood that the invention is not limited to the details of operation disclosed by way of illustration nor by any theory advanced in explanation of the more advantageous results attained, but only by the terms of the appended claims.

We claim as our invention:

1. A process for producing motor fuel from hydrocarbon cracking products boiling in the gasoline range which comprises fractionating hydrocarbon cracking products to separate a normally liquid fraction boiling between 23° C.

and 70° C., substantially devoid of normally gaseous olefins, and comprising normally liquid, monomeric, straight chain olefins, from higher boiling components of said cracking products, admixing isobutane with the separated 70° C. end point fraction in the proportions necessary to form a liquid mixture containing at least five mols of isobutane per mol of olefin present, and adding the liquid mixture to a circulating dispersion of isobutane and reacted cracked gasoline fraction with about 0.7 to 3 volumes of sulfuric acid of at least 85% concentration at about -10° C. to +50° C. while maintaining in the reaction zone a molar ratio of isobutane to olefin of 60:1 to 500:1, whereby alkylation of isobutane by said olefins with formation of isoparaffins having four more carbon atoms per molecule than the individual olefins united with said isobutane takes place and a saturated gasoline of increased lead susceptibility and lowered sulfur content, and which also has a high octane number throughout the boiling range of the reaction products with the octane number of the higher boiling fraction thereof being at least equal to that of the corresponding lower boiling fraction, is obtained.

2. A process for producing motor fuel from hydrocarbon cracking products boiling in the gasoline range which comprises fractionating hydrocarbon cracking products to separate a normally liquid fraction having an end point of not more than 70° C. and comprising normally liquid, monomeric, straight chain olefins from higher boiling components of said cracking products, and alkylating added isobutane with said olefins by feeding said separated lower boiling fraction and from five to ten mols of isobutane per mol of olefin contained in said fraction into a dispersed mixture of isobutane, reacted fraction and sulfuric acid of 85% to 100% concentration at about -10° C. to +50° C., withdrawing reacted mixture after a time of reaction sufficient to substantially saturate said olefinic content while maintaining in the reaction zone a molar ratio of isobutane to olefin of 60:1 to 500:1 and a volume ratio of acid phase to hydrocarbon phase of 0.7:1 to 3:1, whereby said olefins are chemically combined with isobutane to form isoparaffins having four more carbon atoms per molecule than the individual olefins united with said isobutane and a saturated gasoline of higher lead susceptibility and lowered sulfur content

is obtained which has a high octane number throughout the boiling range of the reaction products.

3. A process for producing motor fuel from hydrocarbon cracking products boiling in the gasoline range which comprises fractionating hydrocarbon cracking products to separate a fraction having an end point below 72° C. and comprising normally liquid, monomeric, straight chain olefins, from higher boiling components of said cracking products, and alkylating an added isoparaffin with said olefin in the presence of a volume excess of concentrated sulfuric acid over the hydrocarbons in the liquid phase while maintaining in the reaction zone a molar ratio of said isoparaffin to olefin of at least 60:1 whereby said olefins are chemically combined with said isoparaffin to form higher boiling paraffin hydrocarbons essentially possessing that number of carbon atoms per molecule which corresponds to the sum of the carbon atoms of the individual olefin and isoparaffin united and a saturated product of increased lead susceptibility and lowered sulfur content is obtained

25 which has a high octane number throughout the boiling range of the reaction products.

4. A process for producing motor fuel from hydrocarbon cracking products boiling in the gasoline range which comprises fractionating hydrocarbon cracking products to separate a normally liquid fraction having an end point of not more than 70° C. and comprising normally liquid, monomeric, straight chain olefins, from higher boiling components of said cracking products, and alkylating added isoparaffin with said olefinic content in the presence of concentrated sulfuric acid at -10° C. to +50° C. for a time sufficient to substantially saturate the olefinic content of said fraction while maintaining in the reaction zone a molar ratio of said isoparaffin to olefin of at least 60:1 and a volume ratio of acid phase to hydrocarbon phase of 0.7:1 to 3:1 whereby said olefins are chemically combined with said isoparaffin to form higher boiling paraffin hydrocarbons essentially possessing that number of carbon atoms per molecule which corresponds to the sum of the carbon atoms of the individual olefin and isoparaffin united and a saturated product of increased lead susceptibility and lowered sulfur content is obtained.
